UNITED STATES PATENT OFFICE.

EDWARD FUNKE, OF NEW HOLSTEIN, WISCONSIN.

ACETYLENE-GAS MACHINE.

SPECIFICATION forming part of Letters Patent No. 650,312, dated May 22, 1900.

Application filed October 19, 1899. Serial No. 734,078. (No model.)

To all whom it may concern:

Be it known that I, EDWARD FUNKE, a citizen of the United States, residing at New Holstein, in the county of Calumet and State of Wisconsin, have invented a new and useful Acetylene-Gas Apparatus, of which the following is a specification.

My invention relates to improvements in acetylene-gas apparatus of that character which employ a battery of two or more generators, which on the exhaustion of the carbid in one generator is operable to cut off the exhausted generator and to induct into service another generator having an active charge of gas-making material.

One object of my invention is to provide means by which a fresh generator may automatically be brought into condition for service by turning on the water-supply thereto when the available gas-supply is reduced and the other generator becomes exhausted, whereby the necessity for the manual operation of valves is obviated and the liability of exhaustion of the gas-supply is minimized.

A further object is to simplify the construction of the switch mechanism, so as to render it efficient and reliable in operation, easily accessible for adjustment and repairs when necessary, and to so dispose the elements of said switch mechanism as to avoid interference with the adjustment of the generators when required for removing the spent carbid and recharging the same with fresh active carbid.

With these ends in view my invention consists in an improved switch mechanism operatively connected with a floatable gas-bell and with water-supply devices to a battery of generators, as will be hereinafter fully described and claimed.

To enable others to understand the invention, I have illustrated a preferred embodiment thereof in the accompanying drawings, forming a part of this specification, and in which—

Figure 1 is a perspective view of an acetylene-gas apparatus having my improved switch mechanism connected operatively with the bell and the generator-battery. Fig. 2 is a vertical sectional elevation through the gasometer and parts of my improvement, one of the generators being shown in elevation.

Fig. 3 is a detail sectional view through one style of generator which may be adopted. Fig. 4 is an enlarged detail view, in side elevation, of my automatic switch mechanism for cutting off the water-supply to one generator and turning on the water-supply to the other generator. Fig. 5 is a sectional plan view of the switch mechanism, taken in the plane indicated by the line 5 5 of Fig. 4.

The same numerals of reference are used to indicate like and corresponding parts in each of the several figures of the drawings.

The gasometer has the usual tank 10 and the floatable gas-bell 11. The generator-battery is shown by the drawings as consisting of two generators 12 13, although the number of generators in the battery may be varied.

To support the operating parts of my switch mechanism which is used in connection with the water-feed devices to the generators of the battery, I have shown a horizontal platform 14, supported in any suitable way on the upper part of the stationary gasometer-tank. 75 To the under side of this platform is connected a horizontal gas-pipe 15, which is provided at its ends with the branches 16 17, arranged to extend in a downward direction toward the generators and suitably coupled to the 80 heads thereof. With the horizontal pipe 15 communicates an off-bearing length of pipe 18, which passes through the gasometer-tank and terminates in an upwardly-extending branch 19, extending through the water seal 85 contained in the tank 10, so as to discharge the gas into the floatable bell 11.

Each generator of the battery is provided near its upper end with an inwardly-extending flange 20, forming a seat for a compressible gasket 21, upon which rests the imperforate head or cover 22, the latter being attached to and suspended by the vertical branch of the gas-pipe. Short posts 23 are made fast with the generator at opposite sides thereof, 95 so as to extend a suitable distance above the cover, and these posts are provided with openings for the reception of the end portions of a horizontal clamp-supporting bar 24, the latter extending across the generator-head. (See 100 Fig. 3.) In this bar is mounted a clamping-screw 25, which is adapted to bear upon the head 22 in order to force the latter against the gasket for making a gas-tight joint be-

tween the generator and its cover, the generator being suspended removably from the head, which is attached to the branch of the gas-pipe.

5 The water is supplied to the generators of the battery by feed-pipes 26, which communicate with the water-chamber of the gasometer-tank 10, preferably at a point below the gas-bell, and extend through the heads of the 10 generators for discharging the water thereto, substantially in the manner indicated by Fig. 3. Said pipes 26 are provided with the separate valves 28 29, respectively, said valves adapted to be actuated simultaneously for the 15 purpose of opening the passage in one branch of the water-pipe at the same time that the passage in the other branch of the water-pipe is closed. These valves may be constructed in any suitable way to open and close the 20 water-passage and for the attachment of the valve-actuating rods or shafts, the latter to be hereinafter described.

I will now proceed to describe my improved switch mechanism, which is connected operatively with the floatable gas-bell, to be actuated automatically thereby when one generator becomes exhausted and the available gas-supply is reduced, said switch mechanism being arranged to remain at rest during the 30 rise and fall of the floatable gas-bell within certain limits and adapted to open one valve and close the other valve, as hereinbefore briefly indicated. For the support of the switch mechanism above the floatable gas-bell I employ a vertical frame 30, which is made fast with the platform 14, so as to extend upwardly therefrom. This frame has a central upwardly-extending post 31, which terminates in a fixed guide-arm 32. A substantially-horizontal switch-lever 33 is fulcrumed at its middle to this frame or the post thereof, as at 33^a, and this switch-lever is provided with upwardly-extending locking-arms 34 35, which are arranged in diverging positions and are so proportioned as to have their free ends travel in a path close to the overhanging guide-arm 32, each locking-arm of the switch-lever being provided at its free end with a notch 36. A slideable locking-bolt 37 is fitted in an opening of the overhanging guide-arm for vertical movement therein, the lower end of said bolt being adapted to enter the notch in one or the other of the locking-arms on the switch-lever. This locking-bolt 50 is adapted to be automatically withdrawn from an arm of the switch-lever on the descent of the bell to a certain position through the medium of suitable operative connections, which in the present embodiment consist of a lever 38 and a chain or pliable connection 39. The lever is fulcrumed at a point intermediate its length to the post 31, one end of said lever being connected pivotally with the locking-latch. The chain 39 is fastened 55 to the long arm of the lever and to the upper end of the floatable bell, a permanent allowance of abundant slack being provided in said

chain for permitting the floatable bell to rise and fall within certain limits under fluctuations in the gas-supply without affecting the lever and withdrawing the latch from locking engagement with the switch-lever. The switch-lever carries a weight 40, adapted to automatically move the lever on its fulcrum for reversing the valves; but this movement of the switch-lever under the gravity of the weight is restrained by the locking mechanism. The weight is fitted or connected removably to said lever, so that it may be fitted to either end thereof, and thereby operate the valves in a proper manner to cut off the water-supply to one generator and turn on the water-supply to the other generator. The switch-lever is furthermore provided with a depending arm 41, the lower end of which is connected through suitable arms and links with the valve-actuating rods or shafts 42 43. These rods or shafts are arranged in vertical positions to extend from the water-valves upwardly through the platform, the lower end of each rod being connected in a suitable way with one water-valve to turn the latter when the rod or shaft is rocked. The valves and their actuating-rods are arranged for one valve to be closed when the other is opened, and these rods or shafts are actuated simultaneously by the depending arm on the switch-lever. Horizontal arms 46 47 are arranged in overlapping relation at their inner ends and at the lower end of the depending switch-arm 41, a horizontal bolt 48 being employed to pivotally connect the horizontal arms to the lower extremity of the switch-arm. The valve-actuating rods or shafts are provided at the ends thereof above the platform with the cranks 44, toward which the horizontal arms extend, and these cranks and the horizontal arms are connected by links 49, said links being pivoted by vertical bolts 50 to the horizontal arms on the switch-arm, as clearly shown by Figs. 4 and 5.

The operation is as follows: With the parts in the position shown by Fig. 1 the generator 12 is in service to supply the gas through the pipes 16, 18, and 19 to the gas-bell, while the generator 13 is in reserve with a fresh supply of active carbid. On the exhaustion of the generator 12 and a reduction in the available gas-supply the bell 11 descends until it pulls on the chain with sufficient force to move the lever 38 and retract the latch from the arm 34 of the switch-lever. The weight 40 now depresses one end of the switch-lever so as to move the switch-arm 41 in a direction to rock the valve shafts or rods so as to close the valve 28 for the generator 12 and open the valve 29 to the generator 13. The gas is thus free to pass from the last-named generator into the bell, and on the elevation of the latter the chain is slackened, so that the latch may be adjusted into engagement with the arm 34 of the switch-lever. The weight 40 may now be shifted to the opposite end of the switch-lever, while the generator

12 is removed, the spent carbid discharged therefrom, fresh carbid placed therein, and said generator replaced. As the switch-lever is locked against movement by the weight, 5 the generator 12 will not be brought into service until the generator 13 becomes exhausted. It is evident that the floatable bell may rise and fall within certain limits without actuating the latch-lever and the latch, because 10 the latch-lever is connected with the bell by a pliable chain or its equivalent. The employment of the horizontal actuating-arms and the links between the arms and cranked 15 valve-rod is advantageous, because the parts are prevented from binding, thus enabling the switch-lever to move freely. By having the connecting-arms pivoted to the switch-arm on a horizontal axis said connecting-arms accommodate themselves to the arc of 20 travel of the switch-arm. The links 49 are connected to the arms 46 47 to turn on vertical axes which permit the arms 46 47 to travel with the switch-arm in a manner to properly 25 actuate the cranks of the valve-rod.

Changes may be made in the form and proportion of some of the parts while their essential features are retained and the spirit of the invention embodied. Hence I do not desire to be limited to the precise form of all 30 the parts as shown, reserving the right to vary therefrom.

Having thus described the invention, what I claim is—

1. The combination of a water-tank, a bell 35 therein, generators, valved water connections

between said generators and said tank, said generators having also gas connections communicating with the interior of the bell, operating crank-rods connected to the valves in the water connections, a counterweighted 40 oscillatory switch, connections between the same and the crank-arms, a locking device for said switch, and a lever connected to said locking device and to said bell, for the purpose set forth, substantially as described. 45

2. The combination with water-valves of a generator-battery, and cranked rods connected therewith, of a switch having an arm, connecting-arms pivoted to the switch-arm, and links pivoted to the connecting-arms and 50 fitted to the cranks of said rods, substantially as described.

3. The combination with water-valves of a generator-body, and a floatable bell, of a post having a guide, a lever fulcrumed on the post 55 and connected with said bell, a latch slidably confined in the guide and pivoted to the lever, a switch having the spaced locking-arms and a depending arm, a shiftable counterpoise on the switch, and means connecting 60 the switch-arm with said water-valves, substantially as described.

In testimony that I claim the foregoing as my own I have hereto affixed my signature in the presence of two witnesses.

EDWARD FUNKE.
